CARBURETING APPARATUS

John H. Leslie, II, Winnetka, Ill., assignor to
Stewart-Warner Corporation, Chicago, Ill., a
corporation of Virginia

Application April 26, 1945, Serial No. 590,379

4 Claims. (Cl. 261—40)

1

This invention relates to carbureting apparatus employed in connection with internal combustion engines and it is particularly concerned with a system in which the liquid fuel is delivered to the engine cylinders by separate nozzles by which it is sprayed into the air intake passage for admixture with the air at points adjacent the respective inlet valves of the cylinders.

One object of the invention is to provide a new and improved valve device responsive to variations in the rate of engine air induction for controlling the rate at which the fuel is fed into the intake passage.

Another object of the invention is to provide new and improved means for maintaining a substantially constant air pressure immediately adjacent the point of discharge of each of the nozzles.

A further object of the invention is to provide a new and improved fuel control valve with means responsive to variations in the pressure of the fuel supply to regulate the pressure at which the fuel is fed to the engine intake and to automatically vary the flow of fuel in accordance with changes in the rate of engine air induction.

It is also an object of the invention to provide an internal combustion engine with an auxiliary air supply arranged to furnish a limited quantity of air to each of the engine cylinders independently of the throttle valve which controls the main air supply and to provide a space adjacent the intake passage of each cylinder and in communication therewith to which the auxiliary air is furnished at substantially atmospheric pressure and into which space the fuel feeding nozzle extends so as to be subject to atmospheric pressure at all times in order to insure uniformity of operation of the fuel feeding means.

Other objects and advantages of the invention will appear from the following description taken in connection with the drawings, in which:

Fig. 1 fragmentary side elevation of a multiple cylinder internal combustion engine with the intake passage and air induction tube shown in section;

Fig. 2 is a fragmentary top plan view of the engine shown in Fig. 1 but with the air induction tube shown in transverse section, as indicated at line 2—2 on Fig. 1;

Fig. 3 is a vertical detail section taken substantially as indicated at line 3—3 on Fig. 1 but on a larger scale;

Fig. 4 is a vertical detail sectional view of the fuel feeding valve device being taken substantially as indicated at line 4—4 on Fig. 2.

2

In the fuel feeding and carbureting system to which this invention relates, the liquid fuel is supplied by an engine driven pump and is released to the cylinders by a pressure control valve device which is responsive to variations of the air flow rate to the intake manifold, such variations being produced mainly by adjustment of the throttle valve and by engine load and speed. The liquid fuel is distributed from the control valve device to individual nozzles by which it is sprayed into the intake passage adjacent the inlet valve of each cylinder; but since the pressure in the intake passages varies through wide limits in the course of operation of the engine, it is undesirable to have the outlet orifices of the fuel nozzles subjected to these variations in pressure. It is preferable to arrange the nozzles in such a way that they shall be subject to constant pressure at their discharge openings; then since the fuel is fed to the nozzles at variable pressures, depending upon the air flow rate, the rate of fuel supply can be proportioned properly to the air flow rate and will not be additionally altered by other variable factors such as the pressure in the inlet manifold and intake passages. However, alteration of the proportions of fuel and air can still be effected intentionally, by use of the choke valve.

The drawings illustrate a multiple cylinder engine 10 having an exhaust manifold 12 which may be of conventional design and having an intake manifold 14 which is shown as provided with an air induction tube 16 connected into the middle of the length of the manifold 14 for distributing air to the several branch intake passages 18 each of which leads to one of the engine cylinders. The air induction tube has the usual Venturi form with its constriction at 20 and is fitted with a throttle valve 22 and a choke valve 24. The tube 16 is shown surmounted by an air filter 26.

In addition to the air supplied by the induction tube 16 and intake manifold 14, the cylinders are furnished with a limited auxiliary air supply provided by auxiliary passages 28, 28 extending along opposite sides of the air induction tube 16 and continuing in passages 30, 30, each associated with a portion of the intake manifold 14 and each having branch passages 32 associated with the respective intake passages 18 which lead to the several cylinders. The air intake ports 34 of the auxiliary passages 28 are located adjacent the outer end of the induction tube 16 beyond the choke 24 but in position to receive filtered air from the filter 26; and each of the branch passages 32 connects with the intake passage 18 by

way of a port or orifice 36 which is preferably dimensioned to supply just enough air for idling the engine with the throttle valve 22 completely closed. The auxiliary passages 28, 30 are thus open to atmospheric pressure at all times independently of the adjustment of the choke 24 or throttle 22 and a space in each of their branches 32 adjacent the port 36 is thus maintained constantly at substantially atmospheric pressure.

In addition to furnishing air for idling the engine, each of the ports 36 serves for introduction of the liquid fuel into the air stream by reason of the fact that a fuel injection nozzle 38 is mounted in the top wall of each branch passage 32 in position to discharge a jet or fine spray of fuel across the air gap indicated at 40 in Fig. 3 and directly through the port 36 into the intake passage 18, adjacent the inlet valve 42 of the engine cylinder. Since the discharge opening 44 of the nozzle 38 is spaced back from the port 36 with the air gap 40 interposed, the nozzle will be subject to the substantially uniform atmospheric pressure which is maintained in the auxiliary passage 32.

Fuel is supplied to each of the nozzles 38 by a feed tube 46 having a T-fitting 48 into which the supply tube 50 is coupled. The tube 50 leads from a fuel control valve device denoted generally by the numeral 52 and shown in detail in Fig. 4. The device includes a lower casting 54 containing a fuel chamber 56 with a valve seat fitting 58 screwed into the bottom of the chamber in the inlet passage thereof into which is connected the supply pipe 60 leading from the engine driven pump 62 as shown in Fig. 1. The cast element 54 is surmounted by a second casting 64 and a cover plate 66 with a flexible diaphragm 68 interposed between the parts 54 and 64 and with a larger flexible diaphragm 70 peripherally clamped between the parts 64 and 66. The diaphragm 68 thus forms the top wall of the fuel chamber 56 and it is provided with a centrally disposed button 72 which engages the stem 74 of the fuel inlet valve 76. The valve is normally urged toward its seat 78 by means of a spring 80 disposed below the valve in the valve seat fitting 58.

The cast body element 64 together with the diaphragms 68 and 70 defines a suction or vacuum chamber 82 which is maintained in communication with the air induction tube 16 of the engine by means of a pipe 84 having a terminal fitting 86 which leads from a port 88 located at the construction 28 of the venturi. The chamber 82 and the flexible diaphragm 70 are thus subject at all times to variations in suction produced at the Venturi throat by adjustment of the throttle 22 or the choke 24. Thus, in starting the engine with the choke substantially closed, a high vacuum is produced which pulls strongly against the diaphragm 70 drawing it downwardly in the chamber 82. A pin 90 is clamped to the center of the diaphragm 70 and projects downwardly therefrom into engagement with a small hollow shell 92 secured to the upper side of the diaphragm 68 by the button 72. Thus the downward movement of the diaphragm 70 is transmitted by the pin 90 to the button 72 and to the valve stem 74, forcing the valve open in opposition to its spring 80 and permitting the liquid fuel supplied under pressure by the pump 62 to flow from the orifices 94 into the chamber 56 and thence by way of the pipes 50 and 46 to the nozzles 38. This produces a temporarily rich mixture for starting

the engine and as the choke is opened admitting air, a more correct mixture for continued operation is supplied. The diaphragm 70 is readily responsive to the suction produced at the 5 Venturi throat 28 because the upper side of the diaphragm is exposed to atmospheric pressure through the constantly open vent 86 in the top wall 66 of the fuel control device.

It will be noted that the suction applied to the 10 chamber 82 will act upwardly upon the flexible wall or diaphragm 68 as well as downwardly upon the diaphragm 70, but that because of the larger area of the diaphragm 70, the net result will be a force in the downward direction. This 15 excess force of the suction applied through the diaphragm 70 is sufficient to overcome the force of the fuel pressure acting upwardly against the diaphragm 68 in a direction to permit the fuel inlet valve 76 to close. If the fuel pressure increases, this valve 76 will move toward closed 20 position reducing the rate of flow, and if the fuel pressure is lowered, the valve 76 will open wider, increasing the flow rate. The effects of pressure variations at the fuel pump are thus neutralized, and the final rate of fuel flow is determined by the adjusted position of the diaphragm 70 in response to the suction created by air flow in the induction tube 16.

Fig. 4 shows a spring 100 reacting between the 25 diaphragm 70 and a flange disc 102 carried on the end of an adjusting screw 104 which is threaded into a boss 106 formed in the top wall 66. The valve control mechanism would function as described without the spring 100 but this 30 spring is supplied to counteract or balance the spring 80 which urges the valve 76 toward its seat. The balancing pressure furnished by the spring 100 may then be varied by means of the 35 screw 104 so as to provide the desired adjustment in the effective strength of the spring 80 for seating the valve and this adjustment may be maintained by means of a lock nut 108 on the 40 screw 104.

While there is shown and described herein 45 certain structure embodying the invention, it is to be understood that the invention is not limited thereto or thereby but may assume numerous other forms and includes all modifications, variations and equivalents coming within the scope 50 of the following claims:

I claim:

1. In a charge forming device of a multiple outlet type which mixes a metered quantity of fuel with air immediately adjacent the several outlets, the combination comprising an intake air manifold having an atmospheric opening and a plurality of outlet openings, said air manifold having a Venturi section therein to form a flow meter, a throttle valve downstream of said venturi so that actuation of said throttle valve controls the air delivery rate from all of said outlets while the pressure at said venturi is a function of the flow rate through said manifold and is independent of the pressure prevailing in 60 said manifold downstream of said throttle valve, said manifold having a plurality of openings through the wall thereof each disposed immediately adjacent one of said outlets, a plurality of fuel nozzles each disposed adjacent to and in axial alignment with one of said openings and so disposed as to project jets of fuel from said nozzles through the intervening free space and through said openings and into said manifold immediately adjacent each of said outlets, means forming a second manifold enclosing the 65 70 75 76 77 78 79 80 81 82 83 84 85 86 87 88 89 90 91 92 93 94 separate spaces between each of said nozzles and its associated opening, said second manifold having a connection to said first manifold at a point upstream of said throttle valve, and means including control means responsive to the pressure at said venturi to supply said nozzles with fuel at a pressure which is a function of the Venturi pressure.

2. The combination called for in claim 1 in which said openings are so proportioned as to supply a fixed minimum flow of air from said outlets.

3. A charge forming device having the combination called for in claim 1 and an air filter connected to the atmospheric opening of said air intake manifold whereby said air cleaner serves to remove dust particles and the like from the air stream passing through said air intake manifold and through said second manifold.

4. In a charge forming device for a multiple cylinder combustion engine of the type which mixes a metered quantity of fuel with air immediately adjacent the several engine intake ports, the combination comprising an intake air manifold having an atmospheric opening at one end and a plurality of outlet openings adapted to communicate with the individual engine ports, said air manifold having a Venturi section therein to form a flow meter, a throttle valve downstream of said venturi so that actuation of said throttle valve controls the air delivery rate from all of said outlet openings while the pressure at said venturi is a function of the flow rate through said manifold and is independent of the pressure prevailing in said manifold downstream of said throttle valve, said manifold having a plurality of openings through the side wall thereof each disposed immediately adjacent one of said outlet openings, a plurality of fuel noz-

zles each disposed adjacent to and in axial alignment with one of said openings and so disposed as to project jets of fuel from said nozzles through the intervening free space and through said openings and into said manifold immediately adjacent each of said outlet openings, said openings being so proportioned as to supply an appropriate flow of air to said ports under idling conditions of said engine, means forming a second manifold enclosing the separate spaces between each of said nozzles and its associated opening, said second manifold having a connection to said first manifold at a point upstream of said throttle valve, and means including control means responsive to the pressure at said venturi to supply said nozzles with fuel at a pressure which is a function of the Venturi pressure.

JOHN H. LESLIE, II.
